Primary Examiner — Cynthia M. Chin(74) *Attorney, Agent, or Firm* — Norton Rose Fulbright Canada(57) **CLAIM**

We claim the ornamental design for a blade holder for goalie skate, as shown and described.

DESCRIPTION

FIG. 1 is tridimensional view of a skate including a blade holder for goalie skate according to our new design; FIG. 2 is tridimensional view of the blade holder for goalie skate of FIG. 1;

FIG. 3 is front elevation view thereof;

FIG. 4 is rear elevation view thereof;

FIG. 5 is a first side view thereof;

FIG. 6 is second side view thereof, opposite the first side;

FIG. 7 is a top plan view thereof; and,

FIG. 8 is a bottom plan view thereof.

The broken lines are for the purpose of illustrating portions of the article that form no part of the claimed design.
